HUMIDITY CONTROLLER

Philip F. Maguire, Jr., Providence, R.I., assignor to Grinnell Corporation, Providence, R.I., a corporation of Delaware

Filed June 22, 1961, Ser. No. 118,906
17 Claims. (Cl. 200—61.06)

The present invention relates to improvements in a control for a humidifying system, and more particularly to improvements in the linkage between a humidity sensitive element and an actuator for actuating and deactuating apparatus in the system which adds moisture to the atmosphere in an enclosure.

Certain presently known humidity controllers employ a moisture sensitive membrane which is exposed to the atmosphere in the enclosure and the length of which changes substantially linearly with changes in the relative humidity of such atmosphere. Customarily one end of this membrane is secured to a frame and the other end is connected to a linkage pivoted to the frame and so proportioned and arranged that the changes in membrane length which are relatively small are greatly magnified to produce a substantial movement of the actuator connected to the other end of the linkage. Such magnification is required in devices of this kind because it is necessary to detect changes in relative humidity in the order of 1% or less and to actuate or deactuate the moisturizing apparatus by such small changes. It is impractical to employ membranes of such length that they could accomplish such actuation and deactuation directly and hence the motion magnification referred to above is required.

This motion magnification, however, has the disadvantage that in order to get substantial motion for a small change in relative humidity it follows in these previous devices that there tends to be a very large motion of the actuating part of the linkage when the relative humidity in the enclosure is permitted to change widely from the normally maintained relative humidity, as for example when the moisturizing apparatus is shut down completely. It is undesirable to permit such large linkage movements because a large protective casing is required to accommodate them and because they result in excessive strain on the membrane. Accordingly it has been the practice to restrict such movements and to interpose a spring between the membrane and the linkage to permit the membrane to change its length after the linkage has reached its restraining point without breaking the membrane.

However, in these prior devices these springs have been firm enough and so arranged that they are not substantially deflected by movement of the linkage prior to the restraint thereof, and it follows that after such restraint and because of such deflection these springs impose significant and increasing loads on the membranes particularly when the membranes have shrunk considerably after the linkage is so restrained.

Such spring loading of the membrane is harmful to the membrane and permanently changes its length through stretching so that it is often necessary to recalibrate the controller when the controller is again put in operation in order to obtain the desired control.

This problem is solved in the present invention by providing a linkage which gives the required motion magnification, in which large motions of the actuating end are restrained but in which excessive load on the membrane after restraint is avoided. This solution is achieved in a preferred embodiment of the invention by providing a linkage having at least two members which, although movable with respect to each other during restraint, are held in one relative position with respect to each other and forced to move together as a unit in that position in response to changes in the membrane lengths when the

2

linkage is not restrained; this holding and movement as a unit being accomplished by a force which has a relationship to relative movement of the members from the held position characterized by the force being substantially maximum in the held position and preferably decreasing as the members are moved relative to each other from such held position. This maximum force necessary to so hold the members can be very small because it need only overcome such opposing forces as any pull on the linkage by the switch for the humidifying apparatus, inertia, vibrations and negligible air resistance which might cause relative movement between these parts when the linkage is not restrained. When the motion of the membrane is such that the linkage reaches its restrained position, the only extra load placed on the membrane is that necessary to overcome the above-mentioned slight force holding the parts together for movement as a unit. It follows that this slight additional load is not increased by further membrane shrinkage and is in fact lessened in a preferred embodiment.

Preferably the two members are pivotally connected to each other and the relative movement comprises pivotal movement with respect to each other.

Other objects and advantages of the invention will become apparent from the following description and accompanying drawings which describe and show for illustrative purposes only certain embodiments of the invention.

In the drawings:

FIG. 1 is a front elevation view of a humidity control embodying the present invention.

FIG. 2 is a partially sectioned side elevation view of the control shown in FIG. 1 taken on line 2—2.

FIG. 3 is a diagrammatic view of the linkage and switch of FIG. 1 illustrating one position of this linkage just prior to movement of the members relative to each other from their held position.

FIG. 4 is a view like FIG. 3 illustrating still another position of the linkage after the linkage has been restrained and the members have been moved relative to each other and

FIG. 5 is a diagrammatic view of another embodiment of the linkage of the present invention.

In the drawings, 2 represents the humidity control having a frame base 4 adapted to be secured to building structure in any convenient manner for example by screws 6 which preferably hold the frame base in the upright position shown in FIGS. 1 and 2. A frame shelf 8 is secured to frame base 4 by screws 10 and supports through rods 12a conventional adjustable hook assembly 14 to which is secured through hooks 16 the upper ends of a pair of conventional humidity sensitive membrane elements 18, e.g. gold-beater skins. The lower ends of these elements are in turn connected to the hooks 20 adjustably mounted on the upper end of a connector rod 22, which passes loosely through an aperture 24 in the shelf 8 and which has its lower end pivotally connected at 25 to the upper part 26 of a lever assembly 28 made up of such upper part 26 and a lower part 30 carried thereon. The pivot 25 is spaced from a main pivot 32 connecting the lever assembly 28 to the frame through depending frame shelf lugs 34.

As shown in FIG. 1, the humidity sensitive membrane, connecting rod 22 and pivots 25 and 32 are so disposed that a change in the lengths of elements 18 rotates the lever 28 about the pivot 32.

The lower end of lever part 30 carries a small permanent magnet 36 which upon such rotation of the lever is moved toward and away from a conventional glass enclosed magnetic switch, sold by Mercoid Corporation, Chicago, Illinois size 9-83, normally closed. This switch is actuated in one direction when the magnet is close to it and is actuated in the opposite direction when the

magnet is withdrawn. It is mounted on the frame by a mounting clamp assembly 40 and has electrical leads 42 leading to a terminal block 44, which is coupled to a humidifying apparatus (not shown) controlled by the switch. The swing of the lever 28 about the pivot 32 as a result of changes in the length of membranes 18 causes the lever to move in a plane generally parallel to the plane of the frame base 4 and the mounting assembly 40 locates switch 38 generally in this plane adjacent the path of the magnet. A shortening of the membrane swings the magnet 36 clockwise away from the switch 38 and a lengthening of the membrane swings the magnet counterclockwise toward the switch. If the membrane is lengthening and thereby causing the magnet to move toward the switch, the solid lines in FIG. 1 illustrate the position of the magnet to operate the switch in one direction to turn off the humidifying apparatus. The dot-dash lines 36a in FIG. 1 illustrate the position of the magnet to operate the switch in the opposite direction to turn on the humidifying apparatus when the magnet swings away from the switch. It will be noted that the switch differential (difference between solid lines 36 and dot-dash lines 36a) is quite small and because the change in length of the membrane is magnified many times by the linkage it will be apparent that the switch 38 will turn the humidification apparatus on and off in response to very slight changes in membrane length and therefore in response to very slight changes in relative humidity in the atmosphere.

Preferably, the magnet 36 is prevented from swinging counterclockwise beyond the right hand operative position shown in FIG. 1 by an adjustable screw 64 mounted on the post 52.

Because this apparatus is thus made sensitive to very small changes in relative humidity it necessarily follows that a large decrease in relative humidity from normal operating relative humidity and therefore a large decrease in length of membrane 18 will tend to swing the magnet 36 far to the left in FIG. 1 about the pivot 32. Since normal operating relative humidity is much greater than the natural relative humidity, it follows that when the humidification equipment is shut down such a large relative humidity decrease takes place.

It is undesirable to provide a frame which will enclose and protect the parts and which is large enough to accommodate such a larger swing. Furthermore, if the magnet 36 is permitted to swing far to the left the load on the membrane becomes excessive. Consequently, the swing is restrained by a stop 46 in the path of the lower part 30 of the lever, which stop comprises a roller 48 rotatably mounted on a bracket 50 which is in turn secured to a forked post 52 extending outwardly from the frame base 4. The lower part 30 extends substantially vertically between the arms of this post, as shown.

The lever 28 is divided into the two lever parts 26 and 30 pivoted together at 54 for relative movement with respect to each other to permit the membrane to continue to shorten after the lever part 30 engages the stop 46. Part 26 comprises a block 26a having the pivots 25 and 32 and further comprises a flat strip having a horizontal portion 26b secured to block 26a and extending into a vertical intermediate section 26c, which in turn extends horizontally in the opposite direction into end section 26d. The end of end section 26d is curved downwardly and around to form a hinge 58, in which is received a hinge pin 60. The ends of the pin are journaled in the arms of a yoke 62 extending downwardly from a horizontal top end section 30a of the lower lever part 30. End section 30a extends along and overlies end section 26d and beyond the yoke 62 it extends downwardly into a vertical section 30b, which in turn horizontally extends in the same direction into section 30c. On the same side of pivot 54 as the free end of section 30a, section 30c turns downwardly into vertical section 30d to the lower end of which the magnet 36 is secured. Attached to the top of end section 26d of the upper lever part and spaced

therealong from pivot 54 is a permanent magnet 56 having the shape of a round, flat disc.

This magnet 56 normally attracts the free end portion of section 30a (which portion is of a suitable material to provide such attraction) about the pivot 54 against the top surface of the magnet in the relative positions with respect to each other shown in FIG. 1 to thereby normally hold or lock the lever parts in such relative positions. As a result the lever parts swing together as a unit in response to changes in membrane length over a range having one end defined by the solid line position of the magnet 36 in FIG. 1 and having the other end defined by the position of the magnet 36 in FIG. 3 in which latter position the part 30 engages stop 46. The lever part 30 is so designed that the force of gravity tends to urge this part clockwise about pivot 54 and to urge the end section 30a against the top of the magnet 56 to thereby assist the magnet in holding the two lever parts together so they swing together, as aforesaid.

When the lever part 30 engages the stop 46, as shown in FIG. 3, continued shortening of the membranes 18 and consequent swinging of the lever part 26 clockwise about pivot 32 overcomes the magnetic and gravity forces holding or locking the parts together and forces the parts to move relative to each other about the pivot 54, as shown in FIG. 4. At the same time part 30 is carried bodily upwardly by the pivotal connection 54.

Upon subsequent lengthening of the membranes in response to a rise in relative humidity the parts move back to their locked positions shown in FIG. 3. Initially this moving back takes place because of the force of gravity and then when the end section 30a approaches closely to the magnet 56 it takes place because of the force of the magnet in addition to the force of gravity.

The combined forces of the magnet 56 and gravity are sufficient to keep the lever parts 26 and 30 locked together as shown in FIGS. 1 and 3 while the magnet 36 is moving through the range referred to. These combined forces need not be very great because the opposing forces tending to disrupt the lock, e.g. vibration, inertia, magnetic pull of the switch, etc. are very small. These combined forces should preferably not be too much greater than the disrupting forces (taking into account a safety factor) because the greater the combined forces the greater the load on the membrane to unlock the lever parts.

It is a feature of the invention that the locking or holding forces exerted by the magnet and by gravity are characterized by the fact that they do not substantially increase, and preferably decrease, with relative motion of the lever parts from their locked positions. Consequently, the maximum holding force is applied when the lever parts are in their locked positions, i.e. when relative movement between the parts is zero. The holding force exerted by the magnet decreases with such relative movement.

If desired, the total holding force may be supplied by the force of gravity tending to rotate the part 30 about pivot 54 to locked position with respect to the part 26. For example, in such case the disc 56 is not magnetized and functions only as a spacer. However, it may be desirable to balance any extra weight of the lower part 30 which is needed to provide a more stable lock by a counterweight on the upper part 26 on the opposite side of the pivot 32. In this way the extra weight does not increase the load on the membrane.

Also it is within the scope of this invention to utilize a tension spring 66, as shown diagrammatically in FIG. 5, between the pivoted lever parts 26' and 30' so arranged that the spring force moment decreases with the relative rotation of the arm parts from their locked positions shown in FIG. 5. This is accomplished by connecting the spring between the parts so that the effective moment arm of the spring about the pivot 54' decreases as the spring force increases and so that the product (moment) of the effective arm and spring deflection decreases with relative movement of the parts from their locked positions.

Where the force of gravity is used for locking there may not be any significant change in the locking force when the lever parts move relative to each other as compared to when they are locked together. In such case the holding or locking force is still considered to be substantially maximum when the lever parts are locked together even though, as aforesaid, such force may not decrease appreciably when the parts are moved relative to each other away from lock positions.

It is a feature of the embodiment of the invention shown in FIGS. 1 to 4 to provide means for imparting substantially vertical movement (in the direction of the longitudinal major axis of the humidifier) to the actuating magnet 36 over at least a substantial part of the entire range of movement of the membrane. In FIGS. 1 to 4 this vertical movement is the vertical movement of magnet 36 after the arm 30 engages the stop 46. Such movement reduces the required overall lateral dimension of the humidifier (minor axis of the humidifier) and at the same time permits magnification of the movement of the membrane. Although such movement has a slight lateral directional component the major directional component thereof is in the direction of the longitudinal major axis of the humidifier.

The arrangement shown in FIGS. 1 to 4 has the advantage that during unlocking of the lever parts substantial movement of the area of end section 30a away from magnet 56, which section is normally held to magnet 56 when the lever parts are locked, commences at the right end of such area (as viewed in the drawing) and gradually works its way to the left toward pivot 54 until the whole area moves a distance from the magnet at which the magnet no longer exerts a substantial pull on section 30a. This decreases the force necessary at any instant to move the end section 30a and magnet 56 away from each other and hence reduces the load on the membranes as compared to moving the whole of the above-mentioned area away from the magnet by the same amount at the same time.

I claim:

1. In a humidity control, a linkage for transmitting movement of a humidity sensitive element to movement of an actuator, said linkage comprising at least two lever members movable relative to each other, means for applying a force to at least one of said lever members to hold said members against relative movement with respect to each other over a predetermined operating range of movement of said element whereby they move together as a coupled unit over said range, stop means responsive to further movement of said element beyond said predetermined range for exerting a force on at least one of said lever members to break said holding force and move said members relative to each other against said holding force without substantially increasing said holding force, whereby said moving force need only slightly exceed said holding force.

2. A humidity control according to claim 1, said means for applying said holding force comprising a magnet.

3. A humidity control according to claim 1, said members being so arranged that the force of gravity comprises at least a part of said holding force.

4. In a humidity control, a linkage for transmitting movement of a humidity sensitive element to movement of an actuator, said linkage comprising at least two members movable relative to each other, said members having oppositely facing overlapping sections extending along each other and hinged together at one part by hinge means, means for applying a force to at least one of said members to hold said members against relative movement with respect to each other over a predetermined operating range of movement of said element whereby they move together as a coupled unit over said range, said holding force urging another of said sections spaced from said hinge means toward each other about said hinge means to hold the sections against relative movement with respect to each other

over said range of movement, means responsive to further movement of said element beyond said predetermined range for exerting a force on at least one of said members to move said members relative to each other against said holding force without substantially increasing said holding force, said moving force forcing said other parts of said section away from each other about said hinge means.

5. A humidity control according to claim 4 in which one of said members is pivotally attached to a frame at 10 one point and to said element at another point spaced from said first point for swinging movement about the frame pivot in response to movement of said element, the other member being supported on said one member for swinging movement together as a coupled unit with said 15 one member over said predetermined range.

6. In a humidity control, a linkage for transmitting movement of a humidity sensitive element to movement of an actuator, said linkage comprising at least two lever members movable relative to each other, means for applying a force to at least one of said lever members to hold 20 said lever members against relative movement with respect to each other whereby they move together as a unit over a predetermined operating range of movement of said element, said force having a relationship to relative movement of said lever members with respect to each other characterized by maximum force at zero relative movement, stop means responsive to further movement of said element beyond said predetermined range of movement for exerting a force on at least one of said lever members 25 to control said means for applying a holding force and move said lever members relative to each other against said holding force.

7. In a humidity control comprising a humidity sensitive element, a switch, a lever arm pivotally connected to a frame at one end portion and to said element at an intermediate portion and having a switch actuator at its other end portion swingable towards and away from switch actuating position by swinging movement of said lever about its pivotal connection with the frame in response 35 to movement of said element, the improvement comprising dividing said lever into at least two lever parts, means for urging said parts into locking relationship with each other so that they move together as a unit over a range of movement of said element and means for automatically forcing said parts out of locking relationship 40 with each other against the force urging them into locking relationship and for forcing the parts to move relative to each other without substantially increasing said last-mentioned force in response to further movement of said element beyond an end of said range of movement.

8. In a humidity control having a frame a linkage for transmitting the movement of a humidity sensitive element to movement of an actuator, said linkage comprising first 45 a lever part pivotally connected to said frame by a first pivotal connection, a connector pivotally connected to a portion of said lever part spaced from said first pivotal connection and to said element for rocking said lever part about said first pivotal connection in response to said movement of said element, a second lever part, cooperating means on said first and second lever parts, and including a second pivotal connection therebetween, for supporting said second part on said first part for swinging movement together as a unit about said first pivotal connection over a predetermined range of swing of said first part about said first pivotal connection and for pivotal movement with respect to each other about said second pivotal connection upon further swinging movement of said first part about said first pivotal connection.

9. A humidity control according to claim 8, including 50 means for stopping further swinging movement of said second part with said first part together as a unit when the end of said predetermined range has been reached, whereupon said further swinging movement of said first part about said first pivotal connection forces said first and second parts to move relative to each other about said

second pivotal connection and said second part to move bodily with said second pivotal connection by which it is supported on said first part.

10. A control according to claim 9, said parts having adjacent end sections which extend in opposite directions from the remainder of the parts along each other in spaced oppositely facing relationship with each other, said end section of said second part overlying and being supported by the end section of said first part, a portion of one of said opposed end sections spaced from the free end thereof being pivotally connected to the free end portion of the other end section to form said second pivotal connection therebetween, means for urging oppositely facing portions of said end sections spaced from said second pivotal connection toward each other to hold said sections together for movement as a unit during movement of said first part through said predetermined range.

11. A control according to claim 10, said means for stopping further swinging movement of said second part comprising a stop attached to said frame and located so that it is engaged by said second part at the end of said predetermined range of swing, whereby further swing of said first part forces said oppositely facing portions of said end sections to move away from each other about said second pivotal connection against the force urging said portions toward each other.

12. A control according to claim 11, said parts being so arranged that said oppositely facing portions of said end sections are urged toward each other about said second pivotal connection by the force of gravity, whereby said force of gravity comprises at least a part of said means for urging said oppositely facing end sections toward each other.

13. A control according to claim 11, said means for urging said oppositely facing portions of said end sections toward each other comprising a magnet.

14. A control according to claim 11, said end sections being horizontal.

15. A control according to claim 14, the end section of said first part extending from the end thereof opposite the pivoted end portion into an intermediate, upwardly ex-

tending vertical section which in turn extends into a second horizontal end section, said last-mentioned horizontal end section extending from the intermediate vertical section in a direction opposite from the direction in which said first end section of said first part extends, the free end part of said second end section being pivotally connected to said frame to form said first pivotal connection.

16. A control according to claim 15, said end section of said second part being generally horizontal and comprising a top horizontal leg of a generally C-shaped portion of said second part, said C-shaped portion comprising in addition to said horizontal end section, a vertical section which extends downwardly from said end section to form the base of the C and then horizontally in the same direction as said end section and beyond said second pivotal connection into the other leg of the C which in turn extends downwardly through a yoke attached to the frame into a vertical leg, a magnet at the lower end of said leg for actuating a mercury switch when it is brought in close proximity thereto.

17. A control according to claim 16, the free end of said first end section of said first part extending downwardly in and around into a hinge forming a portion of said second pivotal connection, a lug in the form of a yoke extending downwardly from a portion of said end section of said second part which is spaced from the free end thereof and is located at the end portion thereof from which the vertical leg of the C portion extends to provide bearings for a pin received in said hinge to thereby form said second pivotal connection between said end sections, said second pivotal connection being spaced below the plane of said end sections and holding the end section of the second part spaced above the end section of the first part.
